UNITED STATES PATENT OFFICE

WILLIAM ZIMMERMANN, OF PHILADELPHIA, PENNSYLVANIA

DESIGN FOR TEXTILE FABRIC

Application filed February 28, 1933. Serial No. 47,348. Term of patent 3½ years.

To all whom it may concern:

Be it known that I, WILLIAM ZIMMERMANN, a citizen of the United States, residing in Philadelphia, Pennsylvania, have invented a new, original, and ornamental Design for Textile Fabric, of which the following a specification, reference being had to the accompanying drawing, forming part thereof, in which the figure is a plan view of a piece of textile fabric illustrating my new design.

I claim:—

The ornamental design for textile fabric, substantially as shown.

WILLIAM ZIMMERMANN.
